(57) **CLAIM**

The ornamental design for an intranasal catheter, as shown and described.

DESCRIPTION

FIG. 1 is a perspective view of an intranasal catheter according to my new design;

FIG. 2 is a top plan view thereof;

FIG. 3 is a bottom plan view thereof;

FIG. 4 is a rear elevation view thereof;

FIG. 5 is a front elevation view thereof;

FIG. 6 is a side elevation view thereof;

FIG. 7 is an opposite side elevation view thereof; and,

FIG. 8 is a perspective view of the catheter in an extended position.
The broken line showing of the intranasal catheter is included for the purpose of illustrating portions of the “article” and forms no part of the claimed design.

1 Claim, 4 Drawing Sheets
